POSTHOLE DIGGER

Walter James McGarr, Cordele, Ga.

Application February 14, 1945, Serial No. 577,915

3 Claims. (Cl. 255—22)

1

This invention relates to a post hole digger.

An object of the invention is the provision of a device which may be readily attached to a tractor so that the borer may be driven from the power take-off of said tractor, while the borer is advanced into the ground by means of hydraulic power, said borer being retracted to an inoperative position, either by a spring in cooperation with the fluid which has advanced the bit or borer, or the bit may be retracted by the hydraulic fluid per se.

Another object of the invention is the provision of a post hole digger, which is adapted to be attached to a tractor with the bit being revolved from the power take-off, while the bit is advanced into the ground by means of hydraulic power operating in a cylinder against the piston connected with the bit, a second cylinder being employed and provided with a piston which moves in opposite directions from the first mentioned piston, so that when the bit has been advanced to its limit in the ground said bit may be returned to its retracted position when the hydraulic power has been applied to the second mentioned piston, said piston being operatively connected together by means of a cable trained on pulleys which rotate in opposite directions.

A further object of the invention is the provision of a power driven post hole digger in which a bit is advanced into the ground during rotation by means of a piston operating in a cylinder through hydraulic pressure, said bit being connected to the piston by means of a shaft which is capable of rotating while the piston is non-rotatable in the cylinder, means being employed for retracting the piston shaft and bit after the hole has been dug.

A still further object of the invention is the provision of a post hole digger adapted to be attached to a tractor, said bit being revolved by operative connections between a shaft carrying the bit and the power take-off of the tractor, said bit being reciprocated by a piston having swivel connections with a shaft, and a second cylinder containing a piston, and a cable connecting the pistons and trained over pulleys rotatable in opposite directions, so that when one piston is lowered the other piston will be raised, a valve being employed for controlling the flow of a liquid under pressure to one cylinder while the liquid in the other cylinder is being exhausted and vice versa.

This invention will be best understood from a consideration of the following detailed description, in view of the accompanying drawings.

2

forming a part of the specification; nevertheless, it is to be understood that the invention is not confined to the disclosure, being susceptible of such changes and modifications as define no material departure from the salient features of the invention as expressed in the appended claims.

In the drawings:

Fig. 1 is a side view in elevation of a tractor 10 showing my post hole digger applied in operative relation thereto.

Figure 2 is a conventional vertical sectional view of the device. It is taken at right angles to Fig. 3 but for the purpose of illustration the two cylinders, shown in staggered relationship on Fig. 5, are located in a common plane together with the rotary drive shaft in order to facilitate the description of the operation of said parts.

Fig. 3 is a fragmentary vertical section at right angles to the section in Fig. 2.

Fig. 4 is a fragmentary end view in elevation of the upper portion of the device.

Fig. 5 is a section taken along the line 5—5 of Fig. 3.

Fig. 6 is a view in perspective of the upper portion of the device with the cap or closure removed.

Fig. 7 is a bottom plan view of the cap.

Fig. 8 is a plan view after the cap or closure and the valve have been removed.

Referring more particularly to the drawings, 10 designates generally a tractor which is capable of being moved under its own power from one position to another for digging post holes along a predetermined line.

This tractor is provided with a shaft 11 forming the power take-off from the tractor. To this shaft is attached a pulley 12 which drives a belt 13 that in turn drives a pulley 14 secured to a shaft 15 extending from the post hole digger which is detachably connected to a frame portion 16 of the tractor in any improved manner. A plate 17 secured to a housing 18 of the digger is adapted to be bolted to the frame 16.

The housing 18 is provided with a cover plate 20. The cover plate 20 is bolted to the top of the housing 18. A pair of cylinders 21 and 22 rise from the cover plate and extend upwardly to a housing 23 which is above the cylinders and is supported by said cylinders. These cylinders may be made independently of the cover plate 20 and a bottom wall 24 of the housing 23. These cylinders may be threaded into openings in the cover plate and also in the wall 24. The shaft 15 is

mounted in bearings 25 in the housing 18, and at its inner end is provided with a tapered gear 26 meshing with a ring gear 27 which is secured at 28 to a collar 29 formed integrally with a sleeve 30 which is located below the cylinder 21 and in axial alignment therewith so that when the gear 27 is revolved the sleeve 30 will likewise be revolved. A keyway 31 is formed in a shaft 32 mounted for reciprocation within the cylinder 21. A key 33 is carried by the sleeve 30, which rides in the keyway 31 when the shaft 32 is moved downwardly or upwardly. Thus, the shaft 32 will be revolved when the sleeve 30 is revolved by the ring gear 27. A bushing 35 is mounted in an opening in a plate 36 which is bolted at 37 to the upper portion of the housing 18. A bushing 38 embraces the sleeve 30 at its lower end and is disposed within a cylindrical depending portion 39 of the housing 18. A packing gland 40 is threaded into the lower end of the member 39 for sealing the lower end of the housing against a loss of oil. Since heavy oil is normally employed in the cylinder 21 some of this oil will work its way into the housing 18 for lubricating the movable elements in said housing;

A bit generally designated by the numeral 41 is removably connected to the outer projecting end of the shaft 32 by a shear pin 42; and this shear pin also connects a wiper 43 to the upper end of the bit. The bit may be of any well-known type, and is provided with spiral flanges 43a which will remove dirt from the hole when it is loosened by the tip 44 on the lower end of the bit. This tip is pinned as shown at 45 to the lower end of the bit so that it may be removed or replaced, if necessary.

A piston 50 is supported by one end 51 of a cable generally designated by the numeral 52. The cable is provided with a yoke 53 which is pivotally connected at 54 to a finger 55 projecting upwardly from the piston 50.

The shaft 32 is provided with a reduced portion 60 to which the piston 50 is swivelly connected so that while the shaft 32 is rotated and lowered the piston 50 will remain stationary except for its reciprocation in the cylinder 21. Bearings 61 and 62 are located on the reduced portion 60 of the shaft 32 provided with spacers 63 and 64 in the form of collars. The collar 64 is supported on a cup-shaped member 65 resting on a collar 66 at the upper end of the shaft 32.

The cable 51 is trained on a pulley 67 keyed to a shaft 68 mounted in the housing 23 (Figs. 2 and 3). A second pulley 69 is also located in the housing 23 and is also secured to the shaft 68. A cable 51a is trained on the pulley 69, but the opposite direction to the training of the cable 51 on the pulley 67, so that when these pulleys revolve in the same direction the cable on one pulley will be wound thereon, while the cable on the other pulley will be unwound. The shaft 68 is supported by plugs or bearings 70 in the side walls of the housing 23. A partition 71 divides the housing into two separate chambers 72 and 73 so that the chamber 72 is isolated from the chamber 73 for a purpose which will be presently explained.

A piston generally designated by the numeral 75 has an eye 76 pivotally connected to a yoke 77 which is secured to the lower end of the cable 51a. A cup-shaped member 78 is supported by a pin 79 from the member 75, and is adapted to close the lower end of the cylinder 22.

Thus, it will be seen that when power is applied to the shaft 15 the gears 26 and 27 through

the key 33 will rotate the shaft 32, and if pressure is exerted on the piston 50 the shaft 32 will be forced downwardly as will be the member 41 so that a hole will be dug in the ground. The pressure employed for driving the shaft 32 downwardly is a liquid under pressure, and when the shaft is moved downwardly the piston 75 will be moved upwardly. On the other hand, when the fluid pressure is exerted against the piston 75, said piston will be moved downwardly while the shaft 32 and the piston 50 will be raised, provision being made for the discharge at that time of the liquid in the upper end of the cylinder 21.

The bottom of the housing 23 is provided with an opening 80 through which liquid passes to and from the cylinder 22. A passage 81 is formed in the bottom of the housing 23 and above the cylinder 21 so that liquid from the chamber 72 will pass to and from the upper end of the cylinder 21.

The upper end of the housing is provided with a valve casing which has a removable cover 82. The cover, and likewise the top 83 of the housing, is provided with complementarily formed semi-circular grooves 84 and 85 respectively, so that when the top is in place a circular passage will be formed to receive a valve 86. This valve is provided with a pair of annular grooves 87 and 88. The top of the housing 83 is provided with a semi-circular groove 90 matching a semi-circular groove 91 and the cover plate 82 to form a cylindrical passage 86a for incoming liquid under pressure. One end of this passage is closed, as shown at 89 (Fig. 4), while the other end is connected to an inlet pipe 92 (Fig. 1) for supplying liquid under pressure to said passage from a pump (not shown) operated by the engine of the tractor. A second passage generally designated by the numeral 93 is closed at one end 89a (Fig. 4) and is formed by a semi-cylindrical groove 94 in the top 83 of the housing 23 and by a semi-cylindrical groove 95 in the cover plate 82 to provide a cylindrical passage through which the liquid is discharged into a pipe 96 which carries spent liquid back to the low pressure side of the pump.

An inspection of Fig. 6 will show that the top 83 is provided with a channel 97 which leads from the crosswise channel 86a to the center channel 84 so that when the groove 87 of the valve 86 alines with a passage 97 liquid under pressure will flow to the cylinder 21 and cause the piston 50, and likewise the shaft 32, to be lowered. When the groove 87 alines with the exhaust passage 99 in the top 83 liquid will be discharged from the cylinder 21 to the passage formed by the semi-circular grooves 94 and 95 whereby the fluid is discharged through the pipe 96 back to the pump.

The groove 88 in the valve 86 is adapted to aline with crosswise inlet passage 100 in the top 83, and since this passage connects the inlet passage 86a with a passage 101 (Fig. 3) communicating with chamber 73 over the cylinder 22. Fluid under pressure will drive the piston 75 downwardly. On the other hand, when the groove 88 in the valve 86 alines with an exhaust pipe 102 in the top 83 the fluid in the cylinder 22 will be discharged into the passage 93 formed by the semi-circular grooves 94 and 95, and will enter the exhaust pipe 96 to be returned to the pump.

It will be noted from Fig. 6 that the passages 97 and 100 in the top 83 are sufficiently extensive to permit the grooves 87 and 88 respectively to allow fluid to enter either chamber 72 or 73.

and similarly passages 99 and 102 permit the fluid to be discharged from said chambers.

The valve 86 is operated manually by a lever 103 pivoted at 104 on the housing 23. This lever is operated by a rod 105 which extends rearwardly and is provided with an operating handle 106 adjacent the seat of the driver. In other words, the valve 86 is shifted longitudinally within its cylindrical passage designated by the numerals 84 and 85 in Fig. 2 for properly positioning said valve for the discharge of fluid from one cylinder while causing fluid under pressure to enter the other cylinder.

The operation of the device shown in Figs. 1 to 8 inclusive is as follows:

Power is supplied to the shaft 15 in any approved manner, as by a clutch mechanism from the power take-off of the tractor which operates the belt 13 trained on the pulleys 12 and 14. The shaft 32 is then rotated together with the borer 41.

The valve 86 is shifted by the rod 105 so that the groove 81 therein will align with the passage 97 so that liquid under pressure from a supply pump will enter the passage 98 in the chamber 72, hence the liquid will enter the passage 81 in the bottom 24 of the housing 23. This liquid under pressure, preferably oil, will act on the piston 50, causing the shaft 32 to descend as well as the borer 41, hence a hole will be cut into the ground. When the shaft and boring tool have reached their lower limit and the wiper 43 has removed the dirt away from the top of the hole the shaft 32 may be returned to its normal inoperative position by moving the valve 86 to a position whence the groove 88 will align with the passage 100 (Fig. 6), so that fluid under pressure will be directed into the cylinder 22 and against the piston 75 so that the piston will be moved downwardly to the position shown in Fig. 2 while the piston 50 will be elevated.

The power take-off is disconnected from the pulley 12 by a clutch mechanism (not shown), and the tractor may then be moved to the next position for drilling a hole and the operations will be repeated.

The piston may be manually operated through a system of gearing and a large hand wheel.

The cylinders 21 and 22 are diagonally disposed as shown in Fig. 5 in order that the cables 51 and 51a may be projected into said cylinders since the cables descend from opposite sides of the pulleys 67 and 69.

It will be appreciated that since the shear pin 45 may be readily removed new tips may be applied to the lower end of the bit 41 or a different type of tip may be substituted when desired.

Furthermore, this shear pin may be broken when the tip meets an obstruction which may cause damage to the various elements of the machine.

I claim:

1. A hole digger comprising a pair of cylinders, a piston in each cylinder, a shaft connected to one piston and having an end projecting below its cylinder, a boring tool connected to the projecting end of the shaft, a cable for each piston having one end connected to its piston, a horizontal shaft extending over said cylinders, a pulley mounted above each piston and fixed to the hori-

zontal shaft, the other end of each cable being trained in opposite directions on the adjacently disposed pulley and connected thereto, a housing enclosing the pulleys and provided with a fluid chamber for each cylinder and in communication therewith, means for supplying each chamber with fluid under pressure, a valve for controlling the flow of fluid to and from the chambers in alternation in such a manner that when one chamber is exhausting the other chamber is being supplied with fluid.

2. A hole digger comprising a housing having a pair of chambers therein, a cylinder for each chamber, each chamber being in communication with its respective cylinder, the top of the housing having inlet and outlet passages for a liquid under pressure to and from the chambers, a valve controlling the flow of liquid to one chamber in alternation with the outflow of liquid from the other chamber, a piston in one cylinder being movable towards one end of said cylinder while the other piston is being moved towards the opposite end of its cylinder, a pulley located over each cylinder, a shaft connecting the pulleys for simultaneous rotation, a cable trained over one pulley in one direction and connected to one piston, a cable trained over the other pulley in a reverse manner and connected to the other piston so that as one piston is elevated the other piston is lowered, means supplying liquid under pressure to the inlet passage, a shaft connected to one piston and reciprocated thereby in one direction, a boring tool on the shaft, and means for rotating said shaft.

3. A post hole digger comprising a vehicle chassis provided with a source of power, a supporting frame mounted on the chassis having vertically disposed bearings, a sleeve carried therein provided with a gear wheel and driving connections between it and the source of power, a drill stem movable longitudinally through the stem and rotated thereby, a cylinder carried by the frame and enclosing the upper end of said stem and provided with a piston head for moving the stem outwardly of the cylinder, a second cylinder having a piston therein, a head connecting the upper ends of the cylinders having an enlarged chamber for each cylinder, a shaft extending through the chambers and a pulley in each chamber fixed to the shaft, cables attached to the pistons and trained over said pulleys to effect reciprocal movement of the pistons in opposite directions, said head also having pairs of pressure inlet and exhaust ports for each cylinder, a valve for controlling them and a drilling bit attached to the stem.
